PERMANENT WAVE CURLER

Louis J. Sparks, Monticello, Ind., assignor of
one-half to Paul S. Thompson, Monticello,
Ind.

Application March 26, 1934, Serial No. 717,517

4 Claims. (Cl. 132—33)

This invention relates to hair dressing and has special reference to a permanent wave curler.

One important object of the invention is to provide a novel device of this kind having improved means for grasping a tress of hair.

5 A second important object of this invention is to provide an improved curl forming device for such a curler.

A third important object of the invention is to 10 provide a novel arrangement of tress grasping device or clamp and curler arranged for detachable interlocking engagement, after the hair has been wound on the rod.

With the above and other objects in view, the 15 invention consists in general of certain novel details of construction and combination of parts hereinafter fully described, illustrated in the accompanying drawing, and specifically claimed.

In the accompanying drawing, like characters 20 of reference indicate like parts in the several views, and

Figure 1 is a side elevation of the tress clamp or base and rod assembled with the rod clamp opened.

25 Figure 2 is a side elevation of the same parts at right angles to Figure 1 and with the hair wound on the rod.

Figure 3 is a view of the opposite side of Figure 2 with the wrapper applied.

30 Figure 4 is a horizontal sectional view on the line 4—4 of Figure 1.

Figure 5 is a vertical section on the line 5—5 of Figure 4.

35 Figure 6 is an elevation of the device completely assembled, ready for application of the heating unit.

Figure 7 is a vertical section on the line 7—7 of Figure 4, certain parts being shown in elevation.

40 Figure 8 is a horizontal section on the line 8—8 of Figure 6.

In the embodiment of the invention here disclosed there is provided a base member or tress clamp which consists of upper and lower plates 45 10 preferably made of aluminum or other light metal which are each provided with a notch 11 extending inwardly from one edge to about the center of the plate. At the opposite sides from the notches these plates are held in proper spaced 50 relation by a spacer 12 which is preferably made of bakelite or other similar material. This spacer extends to the inner ends of the notches and the edge at these notches is provided with a padding 13 of felt or the like. The notches 11 bifurcate 55 the plates 10 and between the arms of the bifur-

cations at one side of said notches there is pivoted one end of a clamp plate 14 having its inner edge provided with a padding 15 similar to the padding 13. The other or free end of this clamp member 14 slides in and out between the bifurcations on the remaining side of the notches. The free end 5 of the clamp member 14 is provided with a slot 16 wherein is pivoted one end of a link 17 which can swing in and out of this slot and, when the clamp is closed, in and out of a similar slot in the corresponding end of the spacer 12 and when the clamp is closed and the link 17 in the slots the free end of this link projects beyond the rear edge of the spacer 12. To the free end of the link 17 there is pivoted a cam 18 having an operating 10 handle or finger piece 19. As shown best in Figure 5, the clamp 14 may be opened by swinging the handle 19 from its full line position in that figure in a clockwise direction, then swinging the link 17 in a similar direction and finally swinging the clamp 14 to open the notches, the parts being shown in full line position in that figure and partly open in broken lines. The underside of this base is provided with a felt pad 20 and in this base is provided a circular opening 21 located 15 adjacent the inner ends of the notches 11 and across this opening extends a bar or key 22.

In connection with this base, certain winding 20 mechanism is used which consists of a cylindrical rod 23 whereon is mounted, for rotation, a sleeve 24, the said rod being of greater diameter at one end, to provide a head 23a, and having its other end reduced and screw-threaded as shown at 23b to receive a wing nut 25. One end of the sleeve 24 rests upon the shoulder formed by the inner 25 end of the head 23a and its other end is adapted to be engaged by the wing nut 25, whereby it may be clamped against rotation, between said nut and head. To the upper end portion of this sleeve 24 is pivoted a clamping finger 26 of arcuate cross- 30 section and, when in normal position, this finger extends down alongside of the sleeve and partly encircling the same. The head 23a is of a size to fit within the opening 21 and its outer end face is provided with a groove 27, to receive the cross- 35 bar or key 22. The upper end of the sleeve 24 is provided with a suitable finger grip here shown in the form of a butterfly nut, although any form of finger grip that may be found desirable may be used.

40 There is also provided, for use with this invention, the usual wrappers or flannels 29 and a 45 perforated covering tube 30. Those skilled in the art will understand that such flannel wrappers are generally moistened with water or a suit- 50 55

able setting liquid before application. On the lower end of the covering tube 30 there is provided an oppositely disposed pair of locking hooks 31 adapted to engage, by twisting movement of the tube, a pair of headed studs 32 projecting upwardly from the base.

In using this invention the operator separates a tress of hair covering about one square inch from the remainder of the hair on the scalp. 10 The base clamp is opened and this tress is inserted in the notches 11 after which the base clamp is closed, the base being pushed down close to the scalp. The rod, with the nut 25 loosened, is now taken and its clamping finger 26 opened 15 so that the free end of the tress may be inserted between the sleeve 24 and said clamping finger close to the joint of the latter. Upon depressing the clamping finger and holding it thus, the end of the tress is gripped firmly between the 20 finger and sleeve. The sleeve 24 is now rotated to wind the tress from tip to close to the clamp onto the sleeve, the windings wrapping around the clamping finger to hold it in position to clamp the tip of the tress. When all of the tress above 25 the base has been wound in this manner the lower end of the head 23a is inserted in the opening 21 with the key 22 in the groove 27. The sleeve 24 is then rotated until any slack in the tress is wound tightly thereon, whereupon the nut 25 is tightened to clamp the sleeve between 30 it and the inner side of the head 23a, thus holding the sleeve against rotation. The tight wrapping of the tress prevents dislodgement of the head 23a from the opening 21 of the base. The 35 flannel wrapper is now placed around the rod and the hair wound thereon, and the perforated tube is slipped over the wrapper and turned to cause the hooks 31 to engage the studs 32. The device is now ready for the application of the heater element which may be of any desired kind and which is not deemed necessary here to be shown as such heater elements are old and well-known and form no part of the present invention.

There has thus been provided a simple and ef-

ficient device of the kind described and for the purpose specified.

It is obvious that changes may be made in the form, proportions, and construction of the invention from what has herein been shown and described and that such changes may be made without departing from the spirit of the invention. The invention is, therefore, not to be restricted to the exact form herein set forth but is limited only by the scope as claimed. 10

What is claimed is:

1. A permanent wave device including a base having means for clamping a tress, a rod detachably connected to the base, a sleeve rotatably mounted on the rod, a tress clamp carried by the 15 sleeve, and means carried by the rod for locking the sleeve to the rod at times.

2. A permanent wave device including a base having means for clamping a tress, a rod detachably connected to the base, a shoulder on the 20 rod, a sleeve loosely encircling the rod with an end engaging said shoulder, means for clamping the sleeve against the shoulder to prevent rotation of said sleeve and a tress clamp carried by the 25 sleeve.

3. A permanent wave device including a base having means for clamping a tress, a rod removably mounted in the base, a shoulder on the 30 rod, a sleeve loosely encircling the rod with an end engaging said shoulder, a nut threaded on the rod and adapted to engage the other end of the sleeve, and a tress clamp carried by the sleeve.

4. A permanent wave device including a base member provided with a tress clamp, a rod having a grooved end, said base member having an opening therein to receive the grooved end of the rod, a bar extending across said opening to be engaged in said groove whereby to hold the rod against rotation, a sleeve loosely encircling 40 the rod, means for clamping the sleeve to the rod, and a tress clamp carried by the sleeve. 45
